OPPOSED PISTON ENGINE

Marion Mallory, Detroit, Mich.

Application September 30, 1949, Serial No. 118,868

5 Claims. (Cl. 123—51)

1

This invention relates to an opposed piston internal combustion engine of the type where the pistons are connected to respective crank shafts which are mechanically connected to insure two rotations of one to one of the other. Many variations can be made in the timing and manner of charging and exhausting. The present invention comprises firing the charge while both pistons are approximately at their inner dead centers, and exhausting and charging through opposed ports in the cylinder walls in position to be uncovered by the slow moving piston in the outer portion of its travel.

Details will appear as the description proceeds with reference to the drawings forming a part of the disclosure. In these drawings Fig. 1 is a somewhat diagrammatic longitudinal section through one form of the invention, showing the parts at firing with the ejector operating means diagrammatically shown; Figs. 2, 3 and 4 are similar views showing successive stages in the operative cycle, and Fig. 5 is a fragmentary longitudinal section through the operating shaft and associated parts of the ejector operating means.

The engine shown in the drawings comprises a cylinder 10 in which there are opposed pistons 11 and 12 connected by rods 13 and 14 to cranks 15 and 16 on shafts 17 and 18. An exhaust port 19 is shown through one side of the cylinder, and an inlet port 20 through the opposite side of the cylinder admits air from a blower 21, which may carry fuel introduced by injector 22. If preferred, fuel may be introduced by an injector 23 through one side of central portion of the cylinder opposite the usual spark plug 24.

Shafts 17 and 18 are connected by suitable means, such as engagement of spur gears 25 and 26 on the shafts 17 and 18 with gear 26', which insures two rotations of shaft 17 to one of shaft 18.

Preferably the end of the piston 12 is beveled at 27 on the side where inlet 20 is located.

For one method of operation, described below, the spark plug 24 is connected to means for producing a long succession of sparks by a vibrating coil or equivalent means. In the arrangement shown in Fig. 1, rotor 28 is driven in unison with crank shaft 18, by gears 40, 41 and 42 or other suitable means, and contact arm 29, in the construction shown, makes contact with terminal 30 about 30° before piston 12 reaches inner dead center, and thus closes the circuit through battery 31 and primary coil 32. When magnetic action of the primary coil moves armature 33 to separate breaker points 34, the current is inter-

2

rupted until the magnetism created by the primary coil fades to a point where the armature moves away from the coil again causing breaker point 34 to contact. Thus a rapid succession of sparks are induced by secondary coil 35 and cross the spark gap and produce a hot spot.

The fuel injection may be timed in any suitable manner and one means for such timing is shown diagrammatically in Fig. 1 and in partial section in Fig. 5, and may comprise a cam or striker 43 mounted on a shaft 39 operating an arm of a bell crank lever 45, the other arm of which is connected by a rod 46 to a bell crank lever 47 which times the injector 23. Similarly, a cam or striker 48 on shaft 39 may time the injector 22 through bell crank lever 50 and rod 51.

Both pistons are at their inner dead centers, as shown in Fig. 1, when firing takes place. The working stroke lasts as long as the distance between the pistons increases, that is, until piston 11 has passed its outer dead center to a point, indicated in Fig. 2, where the inward movement of the piston 11 equals the outward movement of piston 12. This point will vary somewhat with variation in the proportion of the lengths of the rods to the crank arms, but, as indicated on the drawings, is reached when piston 11 is about 31° past outer dead center and when piston 12 has traveled 105½° past inner dead center. At this point, piston 12 starts to uncover exhaust port 19. Thus the complete expansion of the space between the pistons is utilized in the working stroke.

Shortly after the exhaust port opens at the position shown in Fig. 2, piston 12 begins to uncover port 20, as shown in Fig. 3. Bevel 21 on the end of piston 12 serves to direct the air, introduced through port 20, towards piston 11, so that the introduced air first occupies the space 40 along the upper side of the cylinder, in the position shown in the drawings, and then the space adjacent piston 11, the waste gases being crowded downward and out the port 19. The period, after exhaust starts before port 20 opens, may be varied somewhat, but the arrangement shown, where port 20 begins to open when piston 12 is still about 48° before outer dead center, is recommended. By the time piston 12 reaches outer dead center, piston 11 is at inner dead center, and the pistons are the nearest together that they get during the exhaust period. From that point on, piston 11 moves outward faster than piston 12 moves inward until the exhaust port is closed.

Carbureted gas may be employed to charge the 55 cylinder through port 20, or the preliminary

scavenging may be by uncarbureted air, and fuel may be mixed with the later portion of the air by means of injector 22 or otherwise, or the entire charge of fuel may be supplied through injector 23. Also the engine may be run so that firing is initiated by spark plug 24, or after starting, the motor may be run as a Diesel engine.

To insure proper firing, many engines of the Diesel or semi-Diesel type employ constantly heated "hot spots" to insure firing when the fuel reaches that spot. Fig. 1 shows a modification that may be termed a timed electrically heated hot spot. The electric heating is begun long enough before the fuel injection begins to definitely establish the hot spot before fuel injection and is continued as long as it is helpful. For example, when timed as shown to start the electric heating about 30° before inner dead center, the fuel injection may begin about 20° before dead center, being varied as to exact time in accordance with well known principles.

In this way, the advantages of a "hot spot" are obtained without the wasteful heating of engine gases by the hot spot before it is needed for firing purposes.

Some of the advantages of the timed electrically heated hot spot may be obtained with other types of engines, but it is of especial advantage with the relatively long power stroke and the relatively long period injection of air begins before firing in the engine herein disclosed, as it avoids the unnecessary heating and expansion of gases of the new charge during the relatively long charging period while enabling control of the firing so as to fully utilize the relatively long power stroke.

In my prior Patent No. 2,545,098, dated March 13, 1951, the application for which was co-pending with the present application, there is shown a motor having the same arrangement and timing of work stroke and exhaust, and the broader claims to that arrangement are in that application, but in that application all scavenging and charging air are introduced near the middle of the cylinder lengthwise thereof, while the present application is directed to the introduction of air through a side port governed by the same piston that governs the exhaust.

What I claim is:

1. An internal combustion engine comprising a cylinder, opposed pistons in the cylinder, mechanical connections between the pistons reciprocating one of the pistons twice to one reciprocation of the other piston, means for burning a charge be-

tween the pistons, said connections positioning both pistons at inner dead center when the charge is fired, an exhaust port at the end of the cylinder in which the slow piston works and positioned at a point where the slow piston starts to uncover it when the fast piston has traveled from firing position to a point approximately 31° past outer dead center, an inlet port through the cylinder wall substantially opposite the exhaust port but somewhat nearer the end of the cylinder.

2. An engine in accordance with claim 1 and having the end of the slow piston shaped to direct gases from said inlet towards the other end of the cylinder and the inlet port positioned to open when the slow piston has moved about 26.5° beyond the point where it begins to open the exhaust port.

3. An engine in accordance with claim 1 and having means to direct air under pressure to said inlet, and a valve controlled inlet from a fuel injector into said entering air.

4. An engine in accordance with claim 1 and having means to direct air under pressure to said inlet, and means to inject liquid fuel into the cylinder at firing times.

5. An engine in accordance with claim 1 and comprising means for producing for each power stroke a timed electrically heated hot spot in the cylinder timed to begin shortly before firing and to continue during firing, and means to inject fuel towards said hot spot timed to start injection shortly after the electric heating is started for each power stroke.
